UNITED STATES PATENT OFFICE.

JOEL SASIENI, OF LONDON, ENGLAND, ASSIGNOR TO MAURICE RAPOPORT, EUGENE J. RICH, AND WALTER M. HOLDSTEIN, COMPOSING THE FIRM OF MAURICE RAPOPORT & COMPANY, OF NEW YORK, N. Y.

DESIGN FOR A TOBACCO PIPE.

Application filed July 8, 1925. Serial No. 14,020. Term of patent 14 years.

To all whom it may concern:

Be it known that I, JOEL SASIENI, a subject of the King of England, residing at London, England, have invented a new, original, and ornamental Design for a Tobacco Pipe, of which the following is a specification, reference being had to the accompanying drawing, forming part hereof, which illustrates a perspective view of a tobacco pipe showing my new design.

I claim:

The ornamental design for a tobacco pipe as shown.

Signed at London, England, this 25th day of June, 1925.

JOEL SASIENI.
